DESIGN FOR A HOUSING FOR CATHODE-RAY APPARATUS

Theodore G. Clement, Rochester, N. Y., assignor to Allen B. Du Mont Laboratories, Inc., Passaic, N. J., a corporation of Delaware

Application April 7, 1945, Serial No. 118,893

Term of patent 14 years

(Cl. D26—5)

To all whom it may concern:

Be it known that I, Theodore G. Clement, a citizen of the United States, residing at 470 Rockingham Street, Rochester 7, New York, in the county of Monroe and State of New York, have invented a new, original, and ornamental Design for Housing for Cathode Ray Apparatus, of which the following is a specification, reference being had to the accompanying drawing, forming part thereof.

The figure is a perspective view of a housing for a cathode ray apparatus showing my new design, the rear end of said case being a plain flat wall and the two sides of said case being alike.

I claim:

The ornamental design for a housing for cathode-ray apparatus, as shown and described.

THEODORE G. CLEMENT.
